TYPEWRITER RIBBON

Harold F. E. Dixon, Douglaston, N. Y., assignor to
Columbia Ribbon and Carbon Manufacturing
Company, Inc., Glen Cove, N. Y.

Application August 31, 1940, Serial No. 353,458

1 Claim. (Cl. 197—172)

My invention relates to improvements in type-writer ribbons and more particularly to ribbons of the paper base variety having a coating of carbon ink on one surface thereof. One object of my invention is to provide a ribbon having no ink along, or immediately adjacent to, its edges. Another object is to provide a ribbon having two or more colors of ink thereon which are distinct and separate, and do not overlap or intermingle with each other at their adjacent edges.

Other objects and advantages of the invention will be evident from the following description, or will be obvious to one skilled in the art, or may be learned by the practice or use of the invention.

In this description and in the following claim, I use the term "paper" in its broadest sense and I intend to include therein any membranous material which is suitable or adaptable to the purpose described and claimed.

In the accompanying drawing I have shown, diagrammatically, but not to scale, three of the various forms in which the invention may be put in practice.

Of the drawing

Fig. 1 shows a fragment of ribbon made in accordance with the invention and having but one color of carbon ink coating upon its printing surface.

Fig. 2 shows a fragment of ribbon having two colors of carbon ink coating upon its writing surface.

Fig. 3 shows a fragment of ribbon having three colors of carbon ink coating upon its writing surface.

In the drawing like characters refer to like elements of the invention. A strip 1 of thin paper or other suitable membranous material, forms the base or backing of the ribbon. Upon one surface of this base 1 I apply a coating of adhesive 2 which may be a glue or paste having suitable characteristics. While this coating of adhesive is still wet or tacky I apply to the surface of the strip of backing or base a narrow strip 3 of thin paper upon one surface of which there has previously been placed a carbon ink coating 4.

Figure 1 shows such a construction and it will be noted that the strip 3 bearing the carbon ink 4 is appreciably narrower than the base 1 and is symmetrically located thereon, along its median line, so that none of the carbon ink is immediately adjacent to either edge of the base 1.

In Figure 2 is shown another form of ribbon of the two color type comprising a base strip 1 55

and a coating of adhesive 2, upon which are placed two narrower strips 3 and 3a each having on their exposed surfaces a carbon ink coating 4 and 4a respectively, which coatings may be of different colors. For example the ink coating 4 may be black while the ink coating 4a may be red. It will be noted that the two strips 3 and 3a are so placed on the surface of the base 1 that there is a space between their outside edges and the edges of the base strip. Also, it will be noted that the inner adjacent edges of the strips 3 and 3a do not touch each other and therefore the two colors of ink upon their surface do not overlap or intermingle or blend with each other, but are kept apart and separated by the space between the strips, however slight this space may be.

In Fig. 3 are shown three separate strips designated 3, 3a, and 3b attached by means of the adhesive layer 2 to the base 1. Upon the exposed surface of the strips 3, 3a, and 3b, there are coatings of carbon ink designated 4, 4a, and 4b, which may be of any desired color or colors.

Other forms, which embody the spirit of the invention within the scope of the appended claim are intended to be included in the invention.

The advantages of the invention lie not alone in the use of the product whereby the clean uninked edges of the ribbon protect the hands of the user from becoming soiled and the complete and effectual separation of the colors prevents their intermingling, but there are distinct advantages in the manufacture of the product resulting from the ability to coat wide rolls of paper with the carbon ink and thereafter cut the inked rolls into narrow rolls of the required width to be attached by means of an adhesive to the base or backing strip, either singly or two or more may be applied simultaneously.

Another advantage of the invention lies in the lessened danger of particles of carbon ink known as "fly" being scraped or rubbed from the surface of the ribbon as it passes through the slots located on each side of the point where the type bars strike. When a typewriter ribbon, the ribbon of the variety having a paper or equivalent membranous base, is inked along its edges there is more or less scraping or rubbing of small flakes or particles of ink from the sharply cut edges. These particles get on the paper and lessen the neatness of the work. They get into the type and clog them. They get on the surface of hectograph master sheets and are reproduced on copies made therefrom. These "fly" particles originate almost entirely from the edges of typewriter rib-

bon of the paper variety. The present invention eliminates this source of "fly" particles.

I claim:

A typewriter ribbon comprising a paper base, and a plurality of parallel carbon ink coated strips in the same plane and slightly spaced apart,

adhesively attached to one surface of said base, said adhesive attachment being the sole means for holding the coated strips in their spaced apart position on the base.

HAROLD F. E. DIXON.
